(57) **CLAIM**

The ornamental design for an unfoldable bag, as shown and described.

DESCRIPTION

The claimed unfoldable bag is used to store and carry a variety of content, including without limitation, general merchandise, jewelry, cosmetics, tools, picnic items and toys, and is capable to unfold flat and fold back into erected position.

FIG. 1 is a perspective view of an unfoldable bag in the erected position, showing my new design;

FIG. 2 is a perspective view of an unfoldable bag in the unfolded position. The interior decoration is shown for illustrative purposes only and forms no part of the claimed design;

FIG. 3 is a front elevational view thereof;

FIG. 4 is a rear elevational view thereof;

FIG. 5 is a left side elevational view thereof.

FIG. 6 is a right side elevational view thereof; and,

FIG. 7 is a top plan view thereof.
